WASHING MACHINE

James B. Kirby, West Richfield, Ohio, assignor to
 Industrial Improvements Incorporated, Cleve-
 land, Ohio, a corporation of Ohio

Application June 29, 1928, Serial No. 289,290

18 Claims. (Cl. 68—18)

This invention relates to clothes washing machines and has for its object the provision of a simple, inexpensive, compact and small-sized machine by which small amounts of clothing can 5 be washed and extracted quickly and conveniently.

Most apartment-house dwellers desire at times to do small amounts of personal laundry, yet have no conveniences therefor nor place to store the 10 same if they possessed them; and many others than apartment dwellers desire to do small amounts of washing at different times for which the ordinary large-sized washing machine is unnecessarily cumbersome. The majority of houses, 15 flats, and apartments in America at the present day are equipped with bath-tubs and the main object of my invention is the provision of a simple, compact, readily portable and easily stored machine capable of attachment to and use in such 20 bath-tub for the purpose of washing conveniently small quantities of lingerie and extracting the water centrifugally. Other objects of the invention are the provision of a machine of reversible type which may be moved from one position 25 to be charged and discharged of clothing and fabrics, and moved to a second position for washing and/or extracting. My invention also contemplates new and improved expedients for introducing liquid for washing, wringing, bluing, 30 etc. purposes; while further objects and advantages of the invention will become apparent as the description proceeds.

In the drawings accompanying and forming a part of this application, Fig. 1 is a vertical sectional view of my improved washing machine in 35 operative position inside of a bathtub; Fig. 2 is a sectional view of the same device moved to receiving and discharging position; Fig. 3 is a top plan view of the parts shown in Fig. 1; Figs. 40 4, 5, 6, and 7 are sectional views corresponding to the similarly numbered lines in Fig. 1; Fig. 8 is an enlarged detail view showing the construction of the hollow supporting stem; and Fig. 9 shows a modification.

45 The clothing container of my improved washing machine consists of a hollow cover member 1 symmetrical about a linear axis, and having at one end a hollow tubular neck 2 coaxial therewith, the opposite end of said container being 50 provided with a displaceable body 3 preferably hinged at 4 at one side and secured by a latch 5 at the opposite side. The neck 2 is externally cylindrical and is rotatably journaled into the 55 hollow cylindrical sleeve 6 of the gear box 7, being held against longitudinal movement in one direc-

tion by means of a flange 8 carried by said neck and engaging one wall of the gear box by means of a suitable thrust-bearing 9, and in the other direction by a suitable shoulder 10 formed at the junction of the cover 1 and neck 2. From the 60 neck the cover 1 flares laterally to a maximum diameter at about 12 where it is formed with a plurality of liquid discharge openings 13, after which it is again reduced in diameter for the reception of the bowl portion or body 3 which also 65 has upwardly flaring side walls 14. The interior of the body is provided with one or more suitable blades 15 carried by the side wall and constituting dashers. The exterior of the sleeve 6 is formed with aligned lateral trunnions 18—18 by 70 means of which said neck is pivoted inside a ring 19; and said ring 19 in turn is provided with two oppositely projecting trunnions 20—20 which are journaled in bearings 21 integral with bracket arms 22—22 whose ends are formed with padded 75 feet 23—23 adapted to rest on the rim 24 of a bath-tub with the trunnion 20—20 horizontal and cross-wise of said tub. These brackets are held together by means of collars 25—25 carried by the ends of the trunnions 20, and the trunnions 80 20 and 18 are perpendicular to each other and to the axis of the sleeve 6 so that said neck has a universal movement within the limits permitted by the internal diameter of the ring 19, and is also completely rotatable about the axis defined 85 by the trunnions 20. Of course the device can be supported otherwise than on a bath-tub, as in a sink or basin, but is designed primarily as an article of manufacture and sale which can be 90 applied to and used with any common domestic plumbing fixture customarily used for washing purposes such as a bath tub or kitchen sink without requiring the purchaser to procure and find storage space for a complete liquid casing.

Carried by the gear box 7 is an electric motor 95 30, and inside said gear box is gearing whereby said motor is operatively connected to said container in washing or extracting relation according to the will of the operator. In the present embodiment said motor has its shaft 31 parallel to the trunnions 20 and provided with a spiral gear 32 meshing with a companion gear 33 which is rigid with the spur gear 34 and pinion 35. The pinion 35 meshes with a second spur gear 36 whose face is provided with an eccentric stud 37 connected by means of a pitman 38 with an oscillating rack 39. Slidably mounted on the neck 2, but constrained to turn therewith by means of a key 40, is a hollow sleeve 41, provided with a spur pinion 42, adapted in one position 100 105 110

of adjustment to mesh with the gear 34 by which it is rotated continuously at high speed, or in the other position of its adjustment, shown in dotted lines in Fig. 1, to mesh with the rack 39 by which it and the receptacle are afforded a motion of continuous oscillation. The end of the sleeve 41 (and also in the present embodiment that of the neck 2) projects through the removable cover 44 of the gear box where it is provided with a handle 45. This handle is preferably made with a smooth contour to prevent any possibility of injury to the operator, and is further, preferably, swiveled to the end of the sleeve 41 so that it can be conveniently grasped while the parts are in operation. In the present embodiment I have shown the sleeve 41 and the hub 46 of the handle as formed with registering circumferential grooves between which are introduced a row of steel balls 47 through a suitable aperture in the hub, which aperture is afterwards closed. The handle is preferably formed with a central aperture 48 communicating with the bore of the neck 2, and also is preferably, as shown in Fig. 8, provided with a metal lining sleeve 49 which projects loosely into said stem sufficiently far to overlap the joint. This arrangement permits the insertion of a spray hose 50, with which most bath rooms are equipped, for the introduction of liquid into the container while it is in operating position.

30 The exterior of the container is preferably formed around the openings 13 with a cylindrical seat 60 defined between outwardly projecting rigid fingers 61, and fitting against the seat and guided between said fingers is a segmental ring 62 whose parts are yieldingly held together by tangent springs 63 connected to out-turned brackets 64 with which the adjacent ends of the segments are provided. Also I preferably provide the neck 2 at its junction with the cover 1, with an axially movable check valve 65 adapted to fall into open position when the container hangs downwardly as shown in Fig. 1 and into closed position when the container is moved to the upward position shown in Fig. 2. I preferably provide one of the brackets 22 with a latch 66 (a common cupboard catch or door-bolt works very well) adapted to engage a notch 67 formed in the ring 19 to hold the cover 1 in receiving position shown in Fig. 2. Also the exterior of the neck 6 is provided near its free end with a hollow flaring shield 70 which extends sufficiently far to overlap the apertures 13.

55 The operation of the device is as follows: the container is moved to the position shown in Fig. 2 and the body 3 displaced. The valve 65 falls shut by gravity, and in addition to the fabric articles to be washed, the desired quantity of washing liquid can be added at this time. The container is then closed, the latch 66 withdrawn, 60 and the container is moved to operating position shown in Fig. 1. The motor is now set into operation and the sleeve 41 placed in the position shown in dotted lines in Fig. 1 whereupon a vigorous oscillating motion is afforded to the container with consequent agitation of its contents. Up to this time no substantial leakage of these contents through the apertures 13 has been possible because of the position of these apertures above the normal liquid level and because of the 70 ring 62, (or even without that ring), but upon moving the sleeve 41 to the position shown in Fig. 1, a speed of rapid rotation is imparted to the container, and the centrifugal force thereby produced allows the escape of the liquid contents by way of the apertures 13, first displacing the

ring 62 when the latter is used. Before escaping this liquid causes the fabric articles to float automatically into such position of uniform distribution that little vibration is produced, and that little is readily accommodated by the universal connection between the neck 2 and bracket 22. Rinsing liquid can now be introduced through the hose 50, either with or without stopping the spinning movement. Preferably the sleeve 41 is returned to the position shown in dotted lines in Fig. 1 and sufficient rinsing liquid introduced to allow the clothes to float freely and be brought into close contact with liquid, (although no injury to the fabrics can occur by reason of any operation of the device without liquid), after which the centrifugal extracting operation can be repeated. Bluing if desired can be introduced in the same manner and similarly removed. Disposal of the ejected liquid is effected by means of the tub itself (or other plumbing fixture) which is always provided with a suitable drain 71, and splashing of the extracted liquid is prevented by the shield 70. The operations of washing, rinsing, bluing, together with all extraction of liquid are effected without need for the operator's hands to touch liquid at all, and at the end of the operation the container is moved to the position shown in Fig. 2 and the completely washed clothes removed.

In the modification shown in Fig. 9 the arms 105 22^a of the frame are bent downwardly to stand on a flat surface such as the bottom 75 of a sink. The shield 70^a is a mere ring of metal carried by these arms, and the bowl-shaped body 3^a is merely fastened to the cover 1^a by hooks 110 5^a so as to be raised slightly off the supporting surface. To assemble the bowl-part 3^a is first rested on the surface 75 as shown in dotted lines, then the remaining parts are placed above the same by means of the handles 76. The bowl is 115 next raised, one side at a time and the hooks fastened.

It will be understood that a great many changes can be made therein within the scope of my inventive idea and I do not limit myself 120 to any details except as the same are specifically recited in my several claims which I desire may be construed each independent of limitations contained in other claims.

Having thus described my invention what I 125 claim is:

1. The combination with a stationary domestic plumbing fixture of a clothes washing and extracting machine located inside the same, and comprising a supporting frame, a container constructed to hold detergent liquid when at rest and to discharge said liquid centrifugally into said plumbing fixture when rotated at a predetermined speed, mechanism for selectively agitating the contents of said container and rotating said container at liquid discharging speed, said plumbing fixture serving as a receptor for the extracted liquid.

2. The combination with a stationary domestic plumbing fixture of a clothes washing and extracting machine therein and comprising a supporting frame adapted to engage said plumbing fixture, a container journaled in said frame upon a vertical axis, said container having an imperforate bottom and upwardly flaring walls 145 defining a surface of revolution about said axis, said walls having liquid discharge apertures above normal liquid level, mechanism carried by said frame for selectively agitating the contents of said container and rotating said container 150

about its axis, and a bottomless splash guard surrounding said container outside of said apertures, the stationary plumbing fixture constituting a receptacle for the extracted liquid.

5 3. In a laundry machine, a supporting frame, a container for clothing and detergent liquid, said container comprising a cover and a body, means journaling said cover for rotation about its axis, said body meeting said cover on a plane 10 which is perpendicular to said axis and having upwardly flaring walls which define a surface of revolution about said axis, said container being imperforate below a given level and having liquid discharge apertures at its level of greatest diameter, and mechanism carried by said frame and operatively engaging said cover for agitating the contents of said container and alternatively rotating said container about said axis at such speed as to discharge its liquid contents through 15 said apertures.

20 4. The combination of a portable washer and extractor comprising a receptacle adapted to hold clothing and liquid when at rest, and having slanted and apertured side walls concentric to a vertical axis and adapted to permit centrifugal discharge of liquid on rotation, means for supporting said receptacle above the drainable surface of a stationary plumbing fixture, means for alternatively agitating the contents of said receptacle and rotating said receptacle at high speed about its vertical axis, and a non-revolving open-bottom shell surrounding said receptacle opposite its outlet apertures for arresting the centrifugal inertia of the extracted liquid.

25 5. A centrifugal extracting machine comprising an upright container for liquid and fabrics concentric about a vertical axis, means for rotating said container about said axis for discharging the liquid therefrom, and means for detachably supporting said extracting machine upon the rim of an open-topped casing whereby said casing constitutes a receptacle for the extracted liquid.

30 6. In a washing machine, a container having a bowl portion and a cover portion, means securing said portions together, a blade in said bowl portion, and a frame to which said cover portion is journaled on a vertical axis above said bowl portion, said bowl portion having an upwardly flaring side wall formed as a surface of revolution about 35 said axis and having liquid discharge openings in its upper part and being substantially imperforate below said openings, in combination with mechanism for alternatively revolving and oscillating said cover portion.

40 7. In a washing machine, a container having a cover part and a body part, said cover part having a neck which is pivoted transversely and journaled longitudinally, and said body part being 45 separate from said cover part on a plane transverse to the stem, in combination with means for selectively oscillating and rotating said cover part.

45 8. A washing machine and centrifuge comprising a portable frame, a revoluble container journaled in said frame, operating mechanism carried by said frame for selectively rotating said container or agitating its contents, said container having walls formed as a surface of revolution about the journal axis and imperforate in their bottom part so as to hold both clothes and detergent liquid, said walls flaring upwardly and being apertured in their upper part for the centrifugal discharge of such liquid, said container comprising a body portion and a cover, and said operating mechanism engaging a part of said cover.

50 9. In a clothes washing machine, an exposed container for clothes and liquid, said container comprising a cover and a hollow body operatively attached thereto, a supporting element, a vertical bearing for said cover carried by said supporting element, and two trains of driving mechanism carried by said supporting element and selectively coupled to said cover, one of the same producing a motion of continuous rotation, and the other a motion of back and forth rotation thereof.

8c

55 10. In a clothes washing and extracting machine, an exposed container for clothes and liquid, symmetrical about a vertical axis and having its walls slanted outwardly from each end to a plane of maximum diameter between its ends and there formed with water discharge apertures, an agitating blade located inside said container, the walls of said container being devoid of apertures below its plane of maximum diameter, and a journal bearing for said container located above said plane of maximum diameter.

8d

60 11. In a washing machine, a container for clothes and liquid having a hollow body and a neck at one end thereof, a support adapted to fit in stationary domestic bath tubs or like plumbing fixtures, and a bearing pivoted to said support on a horizontal axis, said bearing having said neck journaled therein on a vertical axis and said body depending vertically below the same, and mechanism for selectively oscillating and rotating said neck about such vertical axis.

100

65 12. As an article of manufacture and sale, a clothes-washing machine and centrifuge comprising, an exposed container for the clothing and liquid, mechanism including an electric motor for agitating the container contents and for rotating said container at high speed to extract and discharge the liquid contents therefrom, and means for supporting said container in a sink or bath-tub with its axis arranged substantially vertically, 70 whereby said sink or bath-tub may constitute a receptacle for the discharged liquid.

110

75 13. As an article of manufacture and sale, an extracting machine comprising an exposed clothing and liquid container adapted to be used in conjunction with any customary sink or bath-tub, which serves as a receptacle for the extracted liquid, and means for supporting and spinning said container about a substantially vertical axis to extract and discharge its liquid contents therefrom.

120

80 14. As an article of manufacture and sale, a washing and extracting machine comprising a frame adapted for introduction into any ordinary domestic sink or bath-tub, a container for clothes and liquid carried by said frame, mechanism carried by said frame to agitate the container contents and to rotate said container to extract the liquid contents, and an open bottomed shield carried by said frame to direct such extracted liquid into the sink or tub.

130

85 15. An extractor comprising a single container for clothes and liquid having apertures in its side wall for the discharge of liquid during rapid rotation, an open bottomed member to which said container is journaled and from which it hangs, and means flexibly supporting said member.

140

90 16. The combination with a casing open at its top, of a laundry machine adapted for suspension inside the same, said machine comprising a container for clothing and liquid, a frame to which said container is journaled on a vertical axis, said frame having provisions for gripping the top rim of said casing for detachably supporting said laundry machine in said casing, an electric motor

145

located above the container, and operative connections between said motor and container for driving the same and extracting liquid from the clothing and from said container, said casing 5 constituting a receiver for the extracted liquid.

17. In a clothes washing and extracting machine, a single container for both clothing and liquid hung on a universal joint and depending therebeneath, and mechanism for washing clothing inside said container and for rotating said container, the walls of said container being imperforate in their lower part and apertured in their upper part and flared upwardly so as to retain liquid when at rest and eject it when rotated. 10

18. In a laundry machine, in combination, a frame adapted to rest upon the drainable surface of a stationary plumbing fixture, a hollow mem- 15

ber journaled to said frame upon a vertical axis and adapted when at rest to contain clothing and liquid, said member having upwardly-slanting walls apertured at a level above its bottom to permit the centrifugal discharge of the liquid 80 contents upon rotation of said member, and substantially imperforate below such apertures to enable it to retain detergent liquid during the washing operation, an open-bottomed shield carried by said frame and surrounding said member opposite said apertures for arresting the centrifugal inertia of the extracted liquid, and driving mechanism located above said member for alternatively rotating said member or agitating its 85 contents. 90
